UNITED STATES PATENT OFFICE.

FELIX DEMAN, OF NEW YORK, N. Y., ASSIGNOR TO LEROY MANUFACTURING COMPANY, OF NEW YORK, N. Y., A CORPORATION OF DELAWARE.

DESIGN FOR A BROOCH.

No. 39,458.

Specification for Design.

Patented Aug. 25, 1908.

Application filed June 20, 1908. Serial No. 439,627. Term of patent 3½ years.

To all whom it may concern:

Be it known that I, FELIX DEMAN, a citizen of the United States, residing at New York, in the county of New York and State of New York, and whose post-office address is 245 West One Hundred and Eleventh street, New York city, have invented a new, original, and ornamental Design for Brooches, of which the following is a specification, reference being had to the accompanying drawing, forming part thereof.

Figure 1 is a plan view of a brooch, showing my new design. Fig. 2 is a side view thereof.

I claim:

The ornamental design for a brooch, as shown.

FELIX DEMAN.
